UNITED STATES PATENT OFFICE.

GEORGE GILL, OF TAUNTON, MASSACHUSETTS, ASSIGNOR TO REED & BARTON, OF SAME PLACE.

DESIGN FOR PICKLE STAND AND BOTTLE.

Specification forming part of Design No. 5,926, dated June 11, 1872.

Specification describing a Design for a Pickle Bottle or Jar and Frame or Stand, invented by GEORGE GILL, of Taunton, in the county of Bristol and State of Massachusetts.

The nature of my design is fully exemplified in the accompanying illustration.

A represents the pickle bottle or jar, made oval in shape. B is its oval cover, surmounted by a cucumber resting on a leaf. C represents the frame or stand, made of an oval form, and resting upon four legs, c. Extending upward from each point of the oval is a handle projection, D, formed of two stems, which cross each other, and whose leaves lie on each side of the fruit.

Having thus described my invention, what

I claim as new, and desire to secure by Letters Patent, is—

1. An oval shape, when applied to the body of a pickle bottle or jar.

2. The oval cover B of a pickle bottle or jar, surmounted by a cucumber resting on a leaf, as described.

3. A pickle frame or stand, C, of oval form, as described.

4. A pickle frame or stand with handle projection D, formed of two stems crossing each other, and having a leaf on each side of the fruit, as described.
